AUTOMATIC WARP STOP MOTION FOR
LOOMS

George F. Bahan, Charlotte, N. C.

Application March 23, 1933, Serial No. 682,836

9 Claims. (Cl. 139—355)

This invention relates to an improved automatic warp stop motion for looms.

One object of the invention is to provide an automatic warp stop motion which will permit the elimination of drop wires for each individual warp thread as well as other mechanism common to the old style warp stop motion so that a greater space will be defined between the rear of the harness and the whip roll, thereby permitting a better fitting to be obtained for the harness with less strain upon the warp threads so that a smoother faced fabric may be produced.

Another object of the invention is to provide an automatic warp stop motion wherein an improved latch is employed in conjunction with the heddle bars which will lock said bars against lateral and longitudinal shifting when in position in the heddle frame, but which may be released for permitting ready disengagement of the heddle bars therefrom when it is desired to remove or install heddles.

A further object of the invention is to provide an automatic warp stop motion wherein an electric circuit is completed between a heddle frame and one or more heddles carried therein when a warp thread or threads become broken, said electric circuit including an armature operable for shifting the shipper handle and stopping the loom.

A still further object of the invention is to provide an automatic warp stop motion wherein the heddle frames and heddles function not only to form the shed but also function to complete an electric circuit for stopping the loom.

A still further object of the invention is to provide an automatic warp stop motion employing a plurality of floating feeler bars which are electrically connected with a plate which is adapted for selectively engaging with the contact surface of what I term "a grasshopper motion" whereby an electric circuit may be completed.

A still further object of the invention is to provide an automatic warp stop motion for looms wherein means is employed for engagement with the lay to permit the lay to operate for shifting a lever and disengaging the shipper handle from operative position.

A still further object of the invention is to provide an automatic warp stop motion for looms employing floating feeler bars which are carried in a groove formed in the lower rail of the heddle frame and wherein springs are employed beneath said bars for maintaining enough pressure upon said bars so that they will be normally urged up-

wardly, said feeler bars being depressible against the tension of said springs by a falling heddle or heddles so that wear upon the feeler bars will be reduced to a minimum.

A still further object of the invention is to provide an automatic warp stop motion wherein the floating feeler bars and heddle bars are carried within the limits of the heddle frame so that the amount of space employed will be reduced to a minimum.

And a still further object of the invention is to provide an automatic warp stop motion for looms which may be readily adapted for use with looms employing standard heddle frames and standard heddles.

Other and incidental objects of the invention not specifically mentioned in the foregoing will be apparent during the course of the following description.

In the drawings forming a part of this application, Figure 1 is a front view showing my improved automatic warp stop motion in front elevation,

Figure 2 is an end view of my device installed on a loom,

Figure 3 is an enlarged fragmentary elevation showing the lower rail of the heddle frame constructed in accordance with my invention,

Figure 4 is an enlarged fragmentary sectional view showing one end portion of the lower rail of the heddle frame,

Figure 5 is an enlarged fragmentary sectional view taken on the line 5—5 of Figure 4,

Figure 6 is an enlarged fragmentary vertical sectional view taken on the line 6—6 of Figure 4,

Figure 7 is an enlarged detail sectional view showing the structure employed for kicking out the shipper handle,

Figure 8 is a horizontal sectional view taken on the line 8—8 of Figure 7,

Figure 9 is an enlarged detail sectional view showing the contacts employed in combination with the shipper handle,

Figure 10 is an enlarged side elevation of the heddle bar latch employed showing the latch in latching position,

Figure 11 is a front elevation showing the heddle bar latch in latching position,

Figure 12 is a vertical sectional view of the heddle bar latch,

Figure 13 is a side elevational view showing the heddle bar latch in unlatched position for permitting the removal of the heddle bar therefrom, and

Figure 14 is a detail section taken on the line 55

14—14 of Figure 1 looking in the direction indicated by the arrows.

Referring now more particularly to the accompanying drawings, the numeral 1 indicates in general a loom frame having the usual beam 2 and cloth roll 3. The lay is indicated in general by the numeral 4. Carried by the loom are the heddle frames 5 and 6 which are identical in construction and a description of one, therefore, will suffice for both.

The heddle frame forming a part of my automatic warp stop motion comprises a top rail 7 and a bottom rail 8 which are connected at their opposite ends by metal tubular end bars 9. The top rail 7 is provided at its opposite ends with end pieces 7' which are shaped to fit tightly about the ends of the rail. As best seen in Figure 5 of the drawings, the ends of the rails are slightly reduced on their sides and tapered to provide a snug fit in the metallic end pieces. Screwed through the upper end pieces are bolts A which lock the tubular end bars and the end pieces 7' as a rigid unit. The bottom rail 8 is of similar construction and is provided with end pieces 9' and bolts B. It is pointed out that, as the rails 7 and 8 may be removed, repairs or replacements to the heddle frame may be readily made. The rails 7 and 8 are preferably rectangular in cross section and are preferably formed of wood. Formed in the upper surface of the rail 8 is a series of grooves 10 which are rectangular in outline and which are disposed medially of the thickness of the rail. As best seen in Figure 4 of the drawings, these grooves are of a depth substantially one-fifth the height of the rail. The several grooves are separated by means of a raised portion 11 disposed between adjacent ends of the grooves. Formed in each of the grooves, near its opposite ends, are recesses 12 and mounted in said recesses are springs 13 which are inclined upwardly to extend above the floor of the grooves. The springs 13 are preferably held in position by means of screws 14 and, as will be observed, the upper extremities of the springs are curved downwardly to provide a smooth upper surface. Mounted in the grooves is a floating feeler bar which is indicated in general by the numeral 15. As best seen in Figure 6 of the drawings, the floating feeler bar is preferably Y-shaped in vertical section and comprises a U-shaped binding member 16 and contact members 17 having their upper extremities provided with laterally extending portions 18. As will be observed, the greater portion of the contact members of the floating feeler bar are confined in adjacent relation within the binding member 16 and the lower end portion of the binding member 16 is rounded and adapted to engage the rounded upper end portion of the springs 13. Secured to the bottom rail 8 at either side thereof are oppositely disposed guide straps 19 having laterally disposed inwardly presented flanges 20 at their upper ends. Two pairs of guide straps are preferably employed for each feeler bar, a pair being disposed at each end of said bar with the flanges 20 normally in engagement with the laterally extending portions 18 of the bar. The floating feeler bars will thereby be effectually retained in position in the grooves 10. The straps 19 are preferably secured in place by means of screws 21.

Mounted on the lower surface of the bottom rail 8, near one end, is a contact plate 22 which is preferably secured in position by means of screws 23. The contact plate is provided with a rounded lower surface 24. Connecting the plate

22 with the straps 19 on one side of the bottom rail 8 is a conductor 25. Mounted on the bottom rail 8, near the opposite end thereof, is a contact plate 26 which is electrically connected to the metal end bar 9 by means of an offset strap 27 and end piece 9'.

Carried above the bottom rail 8 of the heddle frame in spaced relation thereto is a metal heddle bar 28 which is normally maintained in parallel spaced relation above the floating feeler bars 10 by means of heddle bar latches which will be described in detail hereinafter. The heddle bar is adapted to support the lower ends of heddles, a few of which are indicated by the numeral 29. A heddle bar 30 is supported in parallel spaced 15 relation below the top rail 7 by means of the heddle bar latches.

The heddles, heddle bars, heddle end bar latches, and floating feeler bars cooperate for closing an electrical circuit in a manner to be 20 described in more detail hereinafter.

Carried by the frame of the loom is a supporting frame 31 which is provided with a base 32 and diverging arms 33 terminating at their upper ends in bearings 34. Journalized through the bearings 25 34 is a tubular shaft 35 having its end portions extending past the bearing 34 at either end. Associated with the shaft 35, near each end thereof, are upstanding levers 36 which form a part of what I have indicated as "a grasshopper motion" and as two of these motions are employed, the description of the construction of one of them will suffice for both. In addition to the upstanding lever 36, the grasshopper motion includes laterally extending parallel arms 37 and 38 which are best seen in Figure 2 of the drawings, the arm 37 being pivoted to the lever 36 at its upper end portion and the arm 38 being pivoted to said lever 36 near the bearing, indicated by the numeral 39, which journals the shaft 35. Pivotally connected with the outer end portions of the arms 37 and 38 is a striking bar 40 which is provided at its upper end with an integral obliquely disposed supporting arm 41. Straddling the supporting arm 41 is a relatively long inverted 45 U-shaped striking plate 42 having a striking surface 43 at its upper end. The lower end portion of the supporting plate 42 is adapted to receive an electrical conductor, a portion of which is indicated by the numeral 44.

In operation, these grasshopper motions are so disposed that the contact plates 22 and 26 on the bottom rails of the heddle frames 5 and 6 may make contact with the striking surfaces 43 of the striking plates 42. The grasshopper motion, however, is movable for shifting the striking surface into proper operative position relative to the heddle frames as said frames are moved to their lowermost position. The striking plate connected with the grasshopper motion disposed beneath the plate 22 is provided with a conductor 45 which extends into and throughout the length of the shaft 35 into a conduit 46 which is curved and disposed downwardly and extends to the shipper end of the loom. The conductor 44, which is connected to the striking plate of the grasshopper motion disposed beneath the plate 26, extends into the conduit 46. Surrounding the shaft 35 between the bearings 34 and 39 are coiled springs 47. One end of one of the springs is locked to the supporting frame 31 whereas the other end is tensioned against the lever 36 of one of the grasshopper motions. The spring carried on the opposite end of the shaft 35 is connected in a like manner and said springs 75

function to maintain the grasshopper motions under a continual tension.

Mounted on one end of the loom frame is the shipper handle 48 which is pivoted to a bracket 49 by means of a bolt 50. The shipper handle is, of course, connected to suitable mechanism for controlling the loom so that when the shipper handle is shifted the loom is either started or stopped. As best seen in Figure 9 of the drawings, there is mounted on an upright member 51' of the loom frame 1, near the shipper handle, a breaker contact 51 which is insulated from the upright by means of an insulating plate 52. Mounted on the shipper handle, near its lower end and disposed to confront the breaker contact 51, is a second breaker contact 53 which is insulated from the handle by means of an insulating plate 54. Mounted on the upright, near the upper end of the loom, is a stub shaft 55 and swingingly mounted on said stub shaft is a shipper handle engaging member which is indicated in general by the numeral 56. The shipper handle engaging member includes a curved arm 57 which extends across the edge of the shipper handle and has a wedging or cam action thereon, and a depending tongue 58 which is cut away to provide a stop face 59. Mounted on the upright of the loom is a bracket 60, the outer end of which is reduced to receive the face 59 of the tongue 58. The bracket is secured in place by means of a bolt 60'. Pivotaly mounted on the bracket 60, near the outer end thereof, is an inverted yoke 61 which is substantially U-shaped in cross section. As best seen in Figure 7 of the drawings, one of the legs of the yoke is slightly cut away to define a shoulder 61'. A shoe 62 is pivotally carried between the walls of the yoke. Connected with the yoke 61 and disposed at right angles thereto is a lever 62'. Mounted on the upright 51' of the loom, substantially medially of its height, is an electro-magnet 63 and, as best seen in Figure 2 of the drawings, the electro-magnet is provided with a pivoted armature 64. Connecting the outer end portion of the pivoted armature 64 with the lever 62' is a metal rod 65. The rod is severed and a turnbuckle 66 connects the severed end portions so that adjustment between the armature and the lever may readily be effected.

By referring to Figure 1 of the drawings, it will be seen that the conductor 44 is connected to one terminal of the electro-magnet whereas the conductor 45 is connected to one side of a suitable power circuit. It is to be understood that the power circuit may comprise a regular 110 volt supply circuit or a step-down transformer or batteries may be employed in lieu of the 110 volt power circuit, if desired. The conductor 45 is carried to the power source through a conduit 67. The other side of the power circuit is connected to the breaker contact 53 by means of a conductor 68 which extends through the conduit 67. Connecting the breaker contact 51 with the other terminal of the electro-magnet is a conductor 69.

Swingingly connected with the tongue 58, intermediate of its length and extending above the bracket 60, is a pawl bar 70 having a pawl 71 at its outer end. As seen in Figure 1, the inner end of the pawl bar is swingingly mounted in a socket formed in the tongue 58. Pivotaly mounted on the side face of the pawl bar, near its pivoted end, is a locking dog 72 and mounted beneath the dog is a pin 72'. A spring 73 is secured to the hub of the shipper handle en-

gaging member to resiliently contact the upper surface of the pawl bar and normally maintain said bar under downward tension. The pin 72' limits downward swinging movement of the locking dog 72. Mounted on the lay 4, at its upper end, and beneath the race plate thereof, is a bracket 73' and screwed through the lower end of said bracket 73' is a bolt 74 having a head 75 which is provided with a substantially V-shaped notch 76. The bolt is, of course, adjustable in the bracket and is held in adjusted position by means of a lock nut 77.

In operation, the heddle frames are shifted up and down for forming the shed to permit the shuttle, with filling therein, to pass through the shed in the well-known manner. The lay 4, with the usual reed attached thereto, swings in an arc and effects the beating up operation. The warp threads are, of course, carried in the usual heddles and, as the heddle frame shifts downwardly, the warp threads will normally retain the heddles with their lower ends disposed in spaced relation to the feeler bars. If, however, a warp thread should break when the heddle is held upwardly thereby, said heddle will immediately drop and will make contact with the feeler bar disposed therebeneath. When the frame carrying the broken warp thread is shifted downwardly, contact will be made through the heddle, heddle bar and contact plate 26 to the striking plate of the grasshopper motion disposed therebeneath, and thence through the conductor 44 to one side of the electro-magnet. The circuit is completed through the floating feeler bar, conductor 25, and contact plate 22, to the striking plate of the other grasshopper motion and thence to the conductor and to one side of the power circuit. The other side of the power circuit is connected to one of the breaker contacts and the mating breaker contact is connected to the electro-magnet. A complete electric circuit will thereby be formed. The armature 64 of the electro-magnet will be rocked for shifting the yoke and shoe into engagement with the pawl bar 70 and shifting said bar upwardly so that the pawl 71 will be disposed in the path of the bolt 74, which is provided with the head 75, as the lay is swung. The heddle frames make but momentary contact with the grasshopper motions, so that further shifting of said frames will break the circuit. The pawl bar must then be held up into the line of travel of the bolt on the lay until the lay swings the bolt into contact therewith. After the momentary contact with the grasshopper motions by the heddle frame and the upward shifting of the pawl bar, therefore, the pawl bar will be held upwardly by engagement of the locking dog 72 behind the shoulder 61' until the lay swings the bolt 74' into engagement with said bar. The pin 72' will limit the downward swinging movement of the dog 72 so that the dog will always be maintained in proper position. When the head 75 engages the pawl 71, the pawl bar, by the force of the shifting lay, is swung so that the shipper handle engaging member rocks on the edge of the shipper handle and swings the shipper handle to inoperative position so that the loom will immediately come to a stop. The breaker contacts 51 and 53 are, of course, separated by the shifting of the shipper handle and the circuit is opened by the separation of said contacts.

After the broken warp thread has been tied, and it is desired to place the loom into operation, it is necessary only to shift the shipper han-

ble to operative position for starting the loom. The breaker contacts 51 and 53 will be again connected so that the device will be in readiness for another break in the warp thread or threads, 5 should one occur.

Connecting the heddle bars 28 and 30 with the top and bottom rails of the heddle frame, are heddle bar latches which are indicated in general by the numeral 78. The heddle bar latch 10 78 is shown in detail in Figures 10 and 11 of the drawings and reference is particularly directed thereto. The heddle bar latch comprises a threaded shank 79 which is tapered toward its lower end and is preferably sunk into the upper 15 surface of the rails of the heddle frame. The shank is reduced in thickness at the upper end of the threaded portion and is projected upwardly, flattened and enlarged in width to define a keeper plate 80 which extends above the shank 20 a distance substantially equal to the length of the shank itself. The mid-portion of the keeper plate is cut away throughout substantially half its width to define a bar-receiving recess 81 which is rectangular in shape and is adapted snugly to 25 receive the heddle bar therein. Extending transversely through the keeper plate 80, below the bar-receiving recess in spaced relation thereto and medially of the width of the keeper plate, is a stop pin 82. As will be observed, the pin 82 30 projects at either side of the plate. Extending through the upper end portion of the keeper plate 80 is a guide pin 83. Formed on the keeper plate within the recess is a lug 83' which is adapted to project through an aperture in the end of the 35 heddle bar. The lug is of a length equal to the thickness of the heddle bar.

Normally straddling the keeper plate 80, throughout the major portion of its length, is a substantially inverted U-shaped preferably 40 spring steel keeper 84 which is provided with a bight portion 85 at its upper end and parallel walls 86. The opposite corresponding edges of the walls 86 are formed with serrations 87 which will render the keeper adaptable for ready manual engagement. Formed in the walls 86 near the upper 45 end of the keeper and medially of the width of said walls are aligned longitudinally extending oblong slots 88 which receive the guide pin 83 therethrough and the keeper is thereby permitted to 50 slide vertically upon the keeper plate for a distance substantially equal to the length of the slot. Formed on the walls 86 are depending aligned lugs 89 which are slightly bowed toward each other and which are provided with rounded 55 aligned bar-engaging edges 90. The lugs normally extend into the bar-receiving recess throughout substantially three-fourths of the length of said recess and are adapted to engage one of the walls of the heddle bar lying in said recess for firmly 60 clamping the bar in position in said recess. In view of the fact that the keeper is preferably formed of spring steel, the lugs 89 will snap into place when the keeper is shifted downwardly to locked position on the keeper plate. The keeper 65 plate is projected downwardly to a point below the stop pin 82 to define parallel guide fingers 91. The corresponding lower end portions of the guide fingers 91 are turned upwardly upon themselves to define lower guide slots 92, which 70 slidably receive the pin 82, so that when the keeper is shifted downwardly into locked position, the keeper plate will be maintained in proper slid- 75 able relation to the plate. The guide pin 82 will provide a guide so that the keeper will be guided into proper position with the lugs 89 in clamp-

ing relation to the heddle bar lying in the bar-receiving recess 81. The fingers 91 will cooperate with the lugs 89 for firmly clamping the heddle bar in locked position. It will be understood that the keeper 85 and lug 90 will cooperate to retain a heddle bar in the heddle bar latch, and will effectually limit said bar against lateral and longitudinal movement in the heddle frame. When it is desired to release the heddle bar and remove it from the bar-receiving recess, it is only 10 necessary to grasp the keeper at the serrated portion 87 and slide the keeper upwardly. This will disengage the lugs 89 from the heddle bar and will permit the ready removal of the heddle bar from the recess 81. It will be observed that, as the 15 keeper is shifted upwardly, the bowed lug 89 will engage the keeper plate 80 at the upper edge defining the recess so that the walls 86 of the keeper, and consequently the guide fingers 91, will be slightly spread apart which will permit more 20 ready shifting of the keeper on the guide pins so that complete access may be gained to the recess. By removing the pins 82 and 83, it is, of course, possible to remove the keeper 84 if need for repair or replacement should develop. 25

The numeral 93 indicates a heddle bar latch which is of identical construction to the latch 78 but wherein the lug 90 is omitted. The latch 93 is adapted for use at points between the ends of the lower rail, and is used in the same manner 30 as the latch 78.

It is particularly emphasized that in my improved warp stop motion, I have utilized the heddle frame for completing the circuit so that it is not necessary to employ separate drop wires 35 and other attendant mechanism as is common on the old style warp stop motion. Attention is further directed to the fact that the heddle frame employed not only functions in its usual manner, that is of supporting the heddles and warp 40 threads, but also serves as an electric switch for closing an electric circuit and stopping the loom as hereinbefore described. It is to be further emphasized that the floating feeler bar is mounted within the confines of the bottom rail 45 of the frame so that a minimum amount of space is utilized without sacrificing the efficiency of the mechanism. The fact that the floating feeler bars are resiliently supported will insure long life and also positive electrical connection between a dropping heddle and said bar. It should be still further emphasized that the well-known lay also serves a dual duty in my invention in that the bolt and head carried thereby are utilized for shifting the shipper bar to inoperative 55 position and consequently breaking the electrical circuit.

By utilizing my "grasshopper motion" the contact plates carried thereby will be disposed in proper position for the respective heddle frames 60 as they are shifted downwardly in the usual manner so that the electric circuit may be completed effectively.

It is believed that from the foregoing description it will be seen that I have provided a warp 65 stop motion which will operate very efficiently over a long period of time with practically no attention.

Having thus described the invention, I claim:

1. An automatic warp stop motion for looms 70 including a heddle frame having a bottom rail, a heddle bar connected with said rail, a heddle shiftable on said heddle bar and supporting a warp thread, a feeler bar yieldably mounted on the rail and held thereby to a vertical rectilinear 75

path and cooperating with the heddle and heddle bar for closing an electric circuit when the warp thread breaks and drops the heddle, means on the bottom rail for retaining the feeler bar in operative position on the rail and limiting the movement thereof and electrically operated means in the circuit adapted to cooperate with the lay of the loom for stopping said loom when the circuit is closed.

10 2. An automatic warp stop motion for looms including a heddle frame having a bottom rail provided with a longitudinal groove in its upper edge, springs mounted in the groove, a floating feeler bar mounted in the groove and resting on the springs, said springs normally urging the feeler bar upwardly, straps carried on the bottom rail and engageable with the feeler bar whereby said bar will be retained in the groove, a heddle bar mounted on the bottom rail above the feeler bar, a heddle shiftable on said heddle bar and adaptable for carrying a warp thread, said heddle being shiftable into engagement with said floating feeler bar for closing an electric circuit when the warp thread breaks, and electrically operated means in the circuit adapted to cooperate with the lay of the loom whereby the shifting of said lay will cause the movement of the shipper handle to inoperative position for stopping the loom.

3. An automatic warp stop motion for looms including a heddle frame having top and bottom rails provided with metallic end pieces, metallic tubular bars for said frame, means connecting the bars with the end pieces, said rails being formed of insulating material, a heddle bar carried above said bottom rail, means connecting said heddle bar with the end bars, contact plates mounted on the lower surface of the bottom rail, means connecting one of said plates to an end piece, a floating feeler bar mounted on the bottom rail, straps mounted on said rail and retaining said feeler bar in position, means electrically connecting the straps with the other of said contact plates, a heddle carried on said heddle bar and shiftable for engaging its end with the floating feeler bar for closing an electric circuit through the heddle bar, end piece, plates and straps, and electrically operated means connected in the circuit adapted to operate with the lay of the loom to move the shipper handle to inoperative position for stopping the loom.

4. An automatic warp stop motion for looms including, in combination with a loom frame having an upright, a lay and a shipper handle, a curved shipper handle engaging member pivotally mounted on the upright, and extending across the edge of the shipper handle an electromagnet mounted on the upright beneath said member and having an armature, a rod connecting the armature with the shipper handle engaging member and movable upwardly upon energization of the magnet whereby the lay will be caused to rock the shipper handle-engaging member and force the shipper handle to inoperative position and stop the loom, a heddle frame, circuit closing means carried thereby, and means electrically connecting said circuit closing means with said magnet.

5. An automatic warp stop motion for looms including, in combination with a loom frame, a lay and a shipper handle, a supporting frame carried on the loom frame, a shaft carried by said supporting frame, a lever shiftable on said shaft, arms pivoted on said lever, a striking bar pivoted on said arms, a striking plate carried

by said bar, a heddle frame mounted above the supporting frame and having a contact plate adaptable for engagement with the striking plate, circuit closing means carried by said heddle frame and adapted to cooperate with the striking plate for closing the circuit, and means carried by the loom frame and operable for effecting disengagement of the shipper handle from operative position by the lay.

10 6. An automatic warp stop motion for looms including, in combination with a loom frame having an upright, a shipper bar engaging member carried by the upright and having a tongue, a pawl bar carried by the tongue, a dog carried by the pawl bar, a bracket mounted on the upright beneath the shipper bar engaging member and constituting a rest for the tongue, an electromagnet mounted beneath the bracket, means engageable with the dog for connecting the magnet with the pawl bar, means for energizing the magnet when a warp thread is broken whereby to shift the pawl bar into the path of the lay for rocking the shipper bar engaging member and forcing the shipper bar to inoperative position, and means to break the circuit when the shipper bar is placed in inoperative position, said dog retaining the pawl bar in the path of the lay after the circuit is broken.

30 7. An automatic warp stop motion for looms including, in combination with a loom frame having an upright, a shipper handle and a lay, a breaker contact carried by the shipper handle, a breaker contact carried by the upright for engagement with said first-mentioned contact, shipper handle engaging member carried by the upright, a pawl bar extending from the shipper handle-engaging member, a dog mounted on one side of the pawl bar, a shouldered yoke below the pawl bar to be engaged by the dog, an electromagnet carried by the upright, a rod connecting said magnet with said yoke to engage the yoke with the dog, and means for energizing the magnet when a warp thread breaks whereby the pawl bar will be shifted into the path of the lay for rocking the shipper handle-engaging member and forcing the shipper handle to inoperative position.

35 8. An automatic warp stop motion for looms including, in combination with a loom frame having an upright, a lay and a shipper handle, a bracket carried by the lay, a bolt carried by the bracket and having a head provided with a notch, a shipper handle engaging member carried by the upright and having a tongue, a pawl bar shiftable on said tongue and having a pawl end, a dog carried by the pawl bar, a pin carried by said bar beneath the dog, electrically operated means on the upright and adapted for shifting the pawl bar, means connecting the electrically operated means with the pawl bar, a heddle frame carried by the loom frame, circuit closing means carried by the heddle frame, and means electrically connecting said circuit closing means with said electrically operated means, said electrically operated means being energizable by the closing of the circuit for shifting the pawl bar into the path of the lay whereby the pawl end will be adapted to engage in the notch of the head for shifting the shipper handle engaging member and shipper handle and stopping the loom, said dog retaining the pawl bar in the path of the lay after the circuit is broken.

40 9. An automatic warp stop motion for looms including, in combination with a loom frame hav-

ing a shipper handle, a lay, and an upright, shipper handle engaging means carried on the lay a supporting frame mounted on the loom frame, a shaft carried by the supporting frame, levers carried by said shaft at each end thereof, arms carried by the levers, striking bars carried by the arms, striking plates carried by the striking bars, a heddle frame having a bottom rail, a heddle bar carried by the heddle frame, a heddle carried by said heddle bar and normally supported upwardly by a warp thread, a feeler bar carried beneath the heddle bar and heddle, plates mounted on said bottom rail, means connecting one of said plates with said heddle bar, means

connecting the other of said plates with said feeler bar, said heddle being releasable by the breaking of the warp thread for closing an electric circuit between the heddle bar and the floating feeler bar to the plates, and electrically operated means connected with the striking plates and operable for completing the circuit when the striking plates are engaged with said plates on the bottom rail of the heddle bar for actuating the shipper handle engaging means whereby 10 the shipper handle will be shifted for stopping the loom and stopping the loom.

GEORGE F. BAHAN.
